Bartlett Murray

ATTORNEY

UNITED STATES PATENT OFFICE.

ROBERT K. CLARK, OF SPRINGFIELD, MASSACHUSETTS, ASSIGNOR TO THE AMERICAN THREAD COMPANY, OF JERSEY CITY, NEW JERSEY, A CORPORATION OF NEW JERSEY.

SPOOL.

Application filed June 16, 1923, Serial No. 645,776. Renewed November 7, 1925.

To all whom it may concern:

Be it known that I, ROBERT K. CLARK, a citizen of the United States, residing at Springfield, county of Hampden, State of 5 Massachusetts, have invented a certain new and useful Improvement in Spools, of which the following is a full, clear, and exact description.

My invention relates to spools, and has 10 special reference to spools that are particularly adapted to receive a winding of thread of the universal type, and has for its object to provide a novel and improved spool of this character. It further has for its object 15 to provide a spool having novel and improved means for removably securing a head thereto.

The following is a description of my invention, reference being had to the accompanying drawings, in which,—

Figure 1 is a longitudinal sectional view, partly in elevation, of a spool embodying the invention in its preferred form;

Fig. 2 is a transverse sectional view taken 25 on the line 2—2 of Fig. 1; and

Figs. 3 and 4 are detail side elevations of the component parts of the device for securing the removable head of the cop in place, the head being shown in section in Fig. 4.

The spool illustrated in the drawings is 30 provided with a cylindrical tube or core 2 preferably of paper or other fibrous material on which the thread is wound, and is further provided with heads 4 and 6, the head 4 being preferably permanently secured on 35 one end of the core and the head 6 being detachably secured on the other end of the core. The heads 4 and 6 are each made up of a relatively thin flexible annular disk of 40 fibre or other suitable material having its central aperture of substantially the same diameter as the interior of the core 2. The head 4 is further provided with an annular disk 8 of felt or similar material which is 45 laid over the inner face of the fibre disk and is interposed between this disk and the corresponding ends of the core and mass of thread. The head 4 is secured to the core by means of a plug 10 of wood which extends 50 through the central aperture in the head and is driven or otherwise secured in the end of the core so as to bring its flange 12 on its outer end against the outer surface of the head and thus permanently secure the head 55 to the core. If desired nails 13 may be used

to mechanically hold the plug 10 in place. The plug 10 is provided with an axial bore 14.

The head 6 is removably secured to the core by means of a plug 16 of wood or other yielding material which extends through the central aperture in the head and into the end of the core. This plug 16 is provided with a flange 18 on its outer end that abuts the outer surface of the head, and the outer surface of the remaining portion of the plug tapers toward its inner end and is provided with projections forming an annular ridge 20 adjacent to its inner end. The plug is further provided with an axial bore, and its inner end portion is provided with a series of slots or slits 22. A plug 24 is also provided having its outer surface tapering toward one end, and the smaller end of this plug is adapted to be forced, by endwise pressure into the inner end of the bore of the plug 16 so as to spread this split end of the latter plug sufficiently to cause the projections of the ridge 20 to be embedded in the inner surface of the core and thus securely hold the head 6 in place. The plug 24 is provided with an axial bore in alignment with the bore of the plug 14.

With this construction it will be apparent that the head 6 may be easily and quickly removed by driving the plug 24 inwardly, by endwise pressure a sufficient distance to enable the inner end of the plug 16 to return to its normal contracted condition, and thus disengage the projections forming the holding ridge 20 from the core, whereupon the plug 16 may be slipped out of the core and the head 6 removed therewith. When it is desired to replace the head this may be easily done by first inserting the tapering plug 24 in the split end of the plug 16; then slipping the two plugs 16 and 24 into the end of the core so as to cause the flange 18 to hold the head 6 against the end of the core; and then, by means of an implement inserted through the bore of the plug 10, forcing the plug 24 into the plug 16 sufficiently to spread the inner end of the plug 16 the requisite amount to cause the projections of the ridge 20 to be embedded in the core, as above described.

From the foregoing it will be apparent that a simple and strong construction is provided for securing the head 6 to the core in such a manner as to enable it to be easily ap-

plied and removed, and when applied, rigidly and securely hold it without danger of accidental displacement.

As will be evident to those skilled in the art my invention permits of various modifications without departing from the spirit thereof or the scope of the appended claims.

What I claim is:

1. A spool comprising a tube of fibrous material, a head for one end of the tube comprising an annular disk, and means for detachably securing the disk to said end of the tube comprising a tubular plug having a flange on one end and having its inner end portion split longitudinally, extending through the disk and adapted to be inserted into said end of the tube, the outer surface of said inner end portion tapering toward its inner end and provided with an annular ridge, and a tapering plug frictionally held within said tubular plug and adapted to be forced into the inner end of said tubular plug by endwise pressure when the latter is inserted in the end of said tube, so as to spread said inner end portion to cause its ridge to be embedded in said tube.

2. A spool comprising a tube, a head for one end of the tube comprising an annular disk, and means for detachably securing the disk to said end of the tube comprising a tubular plug having a flange on one end and having its inner end portion split longitudinally, extending through the disk and adapted to be inserted into said end of the tube, and a plug frictionally held within said tubular plug and adapted to be forced by endwise pressure into the inner end of said

tubular plug when the latter is inserted in the end of the tube, so as to spread said inner end portion to cause it to grip the inner surface of said tube. 40

3. A spool comprising a tube, a head for one end of the tube comprising a disk, and means for detachably securing the disk to said end of the tube comprising a tubular plug projecting from the inner face of said disk and having its inner end portion split longitudinally and provided with external projections, and means comprising a plug frictionally held within said tubular plug 45 and adapted to be inserted by endwise pressure in the inner end of said tubular plug so as to spread the inner end portion of the latter to cause it to grip the inner surface of said tube. 50

4. A spool comprising a tube, a head for one end of the tube comprising an annular disk, and means for detachably securing the disk to said end of the tube comprising a tubular plug having a flange on one end and having its inner end portion split longitudinally, extending through the disk and adapted to be inserted into said end of the tube, and a rigid plug frictionally held within said tubular plug and adapted to be forced by endwise pressure into the inner end of said tubular plug, when the latter is inserted in the end of the tube, so as to spread said inner end portion to cause it to grip the inner surface of said tube, said plug having 60 its outer end exposed and being adapted to be forced out of said tubular plug by endwise pressure. 65

ROBERT K. CLARK. 70
